(57) **CLAIM**

The ornamental design for a wheel front face, as shown and described.

DESCRIPTION

FIG. 1 is a perspective view of a wheel front face showing a new design.

FIG. 2 is a front view of the wheel front face of FIG. 1; and, FIG. 3 is a side view of the wheel front face of FIG. 1. The broken line showing of the wheel barrel is provided for the purposes of illustrating environmental structure and forms no part of the claimed design.
